DENTAL CHAIR

Norman A. Hana, San Francisco, Calif., assignor to Hek Manufacturing Company, San Francisco, Calif., a partnership of California

Application April 1, 1957, Serial No. 45,527

Term of patent 14 years

(Cl. D15—3)

FIG-1

FIG-3

FIG-2

FIG-3

FIG-4

Fig. 1 is a side elevational view of a dental chair showing my new design;

Fig. 2 is a side perspective view thereof, on a reduced scale;

Figs. 3 and 4 are front and rear perspective views, respectively, on a reduced scale, of the dental chair, with the back in a lowered position.

I claim:

The ornamental design for a dental chair, substantially as shown.
